Henry Biggins of Mount Vernon N.Y
(Assignor to)
Michael Gibney of New York et al
Letters Patent No 698 dated April 3. 1855

The Schedule referred in these Letters Patent and
making part of the same

To all whom it may concern

Be it known that I Henry
Biggins of Mount Vernon, Westchester County State of New York
have produced a new and ornamental design for ornamenting

Wes. 698

the handles of Forks, Spoons or other articles of table cutlery, and I do hereby declare the following to be a full and exact description of the same, reference being had to the accompanying drawings forming a part of this schedule; the same letters of reference wherever they occur referring to like parts.

Figure 1 is a representation of the design on the front side of the Fork.

" 2, is a representation of the design on the back side of the Fork.

Letter A, is a representation of the fork. B is the front shield piece. Around this shield piece, is a representation of a piece of grape vine C. In the middle of it, and forming the head of the shield piece, the vine crosses each other, forming an O. shaped loop of the vine, the ends of which extend down the sides of the shield piece, and then cross each other, in an S. shaped knot across the bottom of the shield piece, thus forming; a raised thread around the entire shield piece directly under the loop O. forming the head of the shield piece; is a branch D, from the vine C, having a centre cluster of grapes E, between two leaves F, F, to complete the ornament at the head of the front shield piece.

Letter G, is a second cluster of grapes pendant from between two leaves h, h, branching from a stem i, from the lower side of the S. shaped entwinings of the vine C. forming the ornament of the lower edge of the shield piece.

Letter K, is a double thread around the stem L. of the fork, the upper ends of which vanish or loose themselves in the entwinings of the grape vine surrounding the shield piece, while the outer thread vanishes or loses itself in the blade of the fork thereby leaving the inner thread which thickens and swells into a knot to cross the shank of the fork to complete the design on the front side of it.

Letter M, is the back shield piece of the fork.

Dec. 698

3

Surrounding the edge of it, is a branch of grape vine *a*, crooping and forming an *O*, shaped loop at the head of the fork, and ^{extending} down the edges of the shield pieces till near the junction of the stem of the fork with the shield piece, where they entwine each other across the lower edge of the shield piece, in an *S*, shaped loop or knot. At the sides of the shield piece ends of the stems of the vine *p, p, p, p*, appear branching from the sides of the vine, as if the edging vine had been formed with three pieces of vine.

From the vine, immediately under the head of the shield, is a branch *R*, of the grape vine from which is suspended a cluster of grapes, between two leaves *r, m*.

Letter *V*, is also another cluster of grapes suspended between two leaves *a, a*, from a stem branching from the lower side of the *S*, shaped entwinings of the vine around the shield piece to complete the ornament of the back shield piece.

Down the sides of the stem of the fork are two raised threads, the upper ends of which terminate in the vine surrounding the shield pieces and the outer one vanishing or losing itself in the heel of the fork, while the inner one loses itself in a branch of grape vine *W* across the heel of the fork, from the middle and lower side of which is a cluster of grapes *x*, between two leaves, covering the heel of the fork thereby completing the design for the back of the fork.

Having now described my design for ornamenting the handles of forks, spoons and other articles, of table cutlery, I will proceed to state what I claim and desire to secure by letters patent of the United States.

What I claim, is the use and combination of the ornamental designs herein before described, with the handles of forks, spoons and other articles of table cutlery for the purpose of ornamenting ^{them} substantially as set forth.
